DOCTOR FRANKLIN OLIVER, OF OAKLAND, CALIFORNIA.

CONVERTIBLE COUPÉ-BODY.

1,267,793.

Specification of Letters Patent.

Patented May 28, 1918.

Application filed September 12, 1914, Serial No. 861,449. Renewed November 3, 1917. Serial No. 200,196.

To all whom it may concern:

Be it known that I, Doctor F. Oliver, a citizen of the United States, residing at Oakland, in the county of Alameda and State of California, have invented new and useful Improvements in Convertible Coupé-Bodies, of which the following is a specification.

This invention relates to a convertible or foldable coupé body for motor driven vehicles and the like.

It is one of the objects of the present invention to provide a convertible or foldable coupé body for motor driven vehicles and the like, which is so constructed that the top and side sections of the coupé may be folded back and down to produce an open car. Another object of the invention is to so arrange the different foldable sections that they may be moved or swung from one position to another with the expenditure of little effort and by a simple manipulation of the controlling or locking mechanism. Further objects will hereinafter appear.

The invention consists of the parts and the construction and combination of parts as hereinafter more fully described and claimed, having reference to the accompanying drawings, in which—

Figure 1 is a side elevation of the coupé. Fig. 2 is a plan section on line 2—2, Fig. 1. Fig. 3 is a vertical section on line 3—3, Fig. 1.

Fig. 4 is a section showing the side sashes in the folded position and also the locking mechanism between the foldable top and the wind shield.

Fig. 5 is a section on line 5—5, Fig. 6. Fig. 6 is a section on line 6—6, Fig. 5.

Fig. 7 is a section on line 7—7, Fig. 8. Fig. 8 is a section on line 8—8, Fig. 7.

Fig. 9 is a vertical transverse section on line 9—9, Fig. 1.

Fig. 10 is a vertical central section on line 10—10, Fig. 1.

More specifically described, the coupé consists, as a whole, of a main rigid body section A, a series of folding sashes B, a folding top C, and a stationary front section or wind shield D. The folding top consists of rear posts 2 hinged, as at 3, to the rear end of the car. Pivotal secured, as at 4, to the front or top edges of the posts 2 is a top section 5, and pivotally secured to the

front edge of the top section 5 is a secondary top section 6.

Pivotal secured to each side of the body A, as at 7, at one end and at the other end to the posts 2, is a pair of telescoping tubular arm supports 8 and 9, and mounted internally of said telescoping tubes are compression springs 10. The tension of the compression springs is directed to resist the downward movement of the tubular arm sections 8 and 9 in the direction of arrow a, or, in other words, to counterbalance the weight of the foldable top, when this is turned back into the dotted line position indicated in Fig. 1.

The sides of the coupé are constructed, as shown in Figs. 1, 2, 3 and 4, and will be as follows: 11 indicates the main door by which entrance is made to the interior of the coupé. This door is mounted upon suitable hinges 12. Mounted on said door and secured to same by hinges 13 is a metal frame 14, interior of which is mounted, on hinges 15, a front sash 16. Secured to the rear side of said frame by hinges 17 is a secondary sash 18. This sash is adapted to be swung about hinges 17 in the direction of arrow b and can thus be folded up against the exterior surface of sash 16. The metal frame 14, upon which the sashes 16 and 18 are mounted, may then be folded inwardly in the direction of arrow c (see Figs. 3 and 4) and can thus be folded down inside of the main body A on the interior face of the door, as shown in Fig. 4.

The metal frame, when in the erected position, is locked to the door by a latch member 19 which is more clearly shown in Figs. 5 and 6. The casing 20 of the latch is secured to the door proper, and the upper end of the latch is provided with a cross arm 21 which is adapted to be inserted through a slot 22 formed in a plate 23 secured to the metal frame. The bolt or latch proper is secured in position by a spring 24 and the latch is turned in opposition to the tension of the spring when the cross arm is to be interlocked with the plate 23. The moment the latch is inserted it is only necessary to release the head 25 of the latch. The spring will then turn the cross arm 21 out of register with slot 22 and will then hold it in this interlocked position.

The secondary sash, 18, as before described, is secured by the hinges 17 to the

2
rear side of the frame 14. The lowermost of these hinges is of ordinary construction, while the upper hinge serves the function of a lock which works in conjunction with the main section 5 of the folding top. The construction of this hinge will be as follows: One part of the hinge, as 26, is secured to the sash 18, while the upper and lower exterior sections 27 of the hinge are secured to frame 14. The bolt 28, extending through the hinged sections 26 and 27, is in this instance reciprocally mounted therein, and the movement of same is limited by a pin 29 which extends into a groove 30 formed in the bolt. Interposed between the bottom of the hinged section 27 and the bolt is a spring 31 which normally tends to hold the bolt in an upper position. The extreme upper end of the bolt extends a considerable distance outside of the hinge and is provided with a head 32 and a groove 33 with which a latch 34 is adapted to engage. This latch, when swung into engagement with the bolt 28, forms a lock between the top section 5 and the metal frame, which not only locks the top to the metal frame but also supports the frame against side play.

From the foregoing description it will be seen that the frame 14, upon which the sashes 16 and 18 are mounted, is locked at two different points, one lock being secured by the lower latch 21 and the other by the latch 34. Each individual sash may be opened into the dotted line position shown at 35 and 36, Fig. 2, about its respective hinges to secure ventilation within the coupé, and they may be locked in this position by any suitable latches or attachments not here shown.

The door 11, together with the frame 14, may be opened at any time when entrance is desired to the coupé, as the frame will swing about the hinges 17 while the door 11 will swing about the hinges 12. The door may similarly be opened when the sashes are folded down, as shown in Fig. 4, as the whole folded structure will then swing about the hinges 12.

When it is desired to open the coupé, it is accomplished in the following manner: Sash 18 is first swung about the hinges 17 until it assumes a position exterior and parallel with the sash 16 where it may be secured by a lock or latch not here shown. Latch 34 is now released. The top section is then slightly lifted in an upward direction and this will release a pair of dowel latches 37, hereinafter to be described. The top section 6 may then be folded rearwardly and inwardly with relation to the section 5. This permits the section 5 to be folded about the posts 2 and the whole top structure to be swung rearwardly, as indicated by the dotted lines in Fig. 1. The lower latch 21

will then be released and the two sashes 16 and 18 folded inwardly, as shown in Fig. 4. The coupé portions of the body, or the sides and top, are thus entirely folded away with the exception of the wind shield front D which is stationary. The dowel latches 37 are secured to the top of the wind shield frame, and interposed between said latches and the top section 6 are compression springs 38. The dowel latches are provided as centering points for the foldable top section 6 and also secure said section against side play with relation to the top of the wind shield and metal frame 14 and connected sashes.

The compression springs 38 act as cushions and permit the top to be drawn down tightly by a suitable form of latch, such as shown at 39 in Fig. 4, thus eliminating rattling of the contacting parts. A similar spring 18^a is interposed between bolt 28 and the top section 5. The latch 39 is held in position by a counterweighted arm 40 when the top is up.

Having thus described my invention, what I claim and desire to secure by Letters Patent is—

1. A convertible coupé for motor vehicles and the like, comprising a main body section, a door in said body, a side frame secured to and foldable on said door, a pair of sashes mounted on the side frame and foldable with relation to each other, and a foldable top to cover the coupé.

2. The combination with a vehicle body having an entrance opening and a door for closing the entrance opening, of an open frame hinged to the upper edge of the door for swinging thereover, a sash hinged to the front side of the frame for closing the latter, and a second sash hinged to the rear side of the frame.

3. The combination with a vehicle body having a foldable top of the character described and a side door, of a side frame carried by and foldable on said door, and a pair of sashes carried by said frame and foldable with relation to each other.

4. The combination with a vehicle body having a foldable top of the character described and a side door, of a side frame hinged to the door which is adapted to be folded down on the inside of the door, means for locking said frame in a vertical position on top of the door, and a pair of sashes carried by said frame and foldable with relation to each other.

5. The combination with a vehicle body having a foldable top of the character described and a side door, of a side frame hinged to the door which is adapted to be folded down on the inside of the door, means on the door for locking said frame in a vertical position on top of the door, means for locking said frame with relation

to the foldable top, and a pair of sashes hingedly secured to said frame.

6. The combination with a vehicle body having a foldable top of the character described and a side door, of a side frame hinged to the door which is adapted to be folded down on the inside of the door, means on the door for locking said frame in a vertical position on top of the door, means for locking said frame with relation to the foldable top, a sash mounted inside of said frame, and a second sash hingedly secured on one side of said frame.

7. The combination with a vehicle body having an entrance opening and a door for closing the entrance opening, of a frame hinged to the upper edge of the door for swinging thereover, a latch on the door, a latch plate carried by the frame and extending outwardly over the latch, and a sash hinged to the frame and adapted to swing over the latch plate.

8. The combination with a vehicle body having an entrance opening and a door for closing the entrance opening, of an open frame hinged to the upper edge of the door for swinging thereover, a sash hinged to the front side of the frame for closing the latter, a second sash hinged to the rear side of the frame, means to lock

the frame over the door, a top for the vehicle, and means to lock the frame to the top.

9. The combination with a vehicle body having an entrance opening and a door for closing the entrance opening, of a sash hingedly connected to the door, and a second sash hingedly connected to the first sash.

10. The combination with a vehicle body having an entrance opening and a door for closing the entrance opening, of a sash hingedly connected to the door, a foldable top carried by the body, and a second sash hingedly connected to the first sash.

11. The combination with a vehicle body having an entrance opening and a door for closing the entrance opening, of a sash hingedly connected to the door, a foldable top carried by the body, a second sash hingedly connected to the first sash, and means connecting the unfolded top to the sashes.

In testimony whereof I have hereunto set my hand in the presence of two subscribing witnesses.

DOCTOR FRANKLIN OLIVER.
